UNITED STATES PATENT OFFICE.

WILLIAM HENRY ETTER, OF MARIETTA, OHIO.

WEATHER-STRIP.

SPECIFICATION forming part of Letters Patent No. 752,390, dated February 16, 1904.

Application filed May 4, 1903. Serial No. 155,608. (No model.)

To all whom it may concern:

Be it known that I, WILLIAM HENRY ETTER, a citizen of the United States, residing a Marietta, in the county of Washington and State 5 of Ohio, have invented a new and useful Weather-Strip, of which the following is a specification.

The invention relates to improvements in weather-strips.

10 The object of the present invention is to improve the construction of hinged weather-strips and to provide a simple and comparatively inexpensive one adapted to be readily applied to a door and capable of automatic operation to swing downward and close the space or crack at the bottom of a door when the same is shut and to swing upward to clear the carpet or other floor-covering when the door is opened.

20 A further object of the invention is to provide a weather-strip of this character capable of ready adjustment to enable it to fit as closely as desired against the sill or floor when the door is shut.

25 Another object of the invention is to enable the parts to be readily adjusted to arrange the weather-strip the desired distance above the floor when the door is opened and to enable the angle of the weather-strip to be readily 30 changed.

With these and other objects in view the invention consists in the construction and novel combination and arrangement of parts herein-after fully described, illustrated in the accompanying drawings, and pointed out in the claims hereto appended, it being understood that various changes in the form, proportion, size, and minor details of construction within the scope of the claims may be resorted to 40 without departing from the spirit or sacrificing any of the advantages of the invention.

In the drawings, Figure 1 is a perspective view of a portion of a door provided with a weather-strip constructed in accordance with 45 this invention. Fig. 2 is a detail perspective view of a portion of the weather-strip, illustrating the position of the parts when the door is nearly closed. Fig. 3 is a vertical sectional view, the door being closed. Fig. 4 is a detail perspective view of the spring. 50

Like numerals of reference designate corresponding parts in all the figures of the drawings.

1 designates a weather-strip constructed of sheet metal or other suitable material and provided at its upper edge with openings 2, forming pintle portions and adapted to receive eyes 3 of leaves or plates 4, which are secured to a door 5, whereby the weather-strip is hinged to the same. The weather-strip is provided with an interior lining 6, of felt or other suitable material, which fits against the door when the same is closed and which projects beyond the lower edge of the weather-strip to provide a tight joint or connection at the bottom of the door and to effectually exclude air from the crack or space beneath the door. The lining 6 projects beyond the lower edge of the weather-strip sufficiently to compensate for any irregularity of the surface of the sill or the floor, whereby a draft beneath the door is effectually prevented.

The leaf or plate 4, which may be tapered, as shown, or of any other ornamental configuration, is provided at the bottom with a tongue or extension which is coiled or bent around the pintle portions of the weather-strip 1 to form the projecting eye 3. The said plate or leaf fits flat against the face of the door and is adjustably secured to the same by means of a screw 7, which extends through a slot 8 of the leaf or plate. The slot 8 is disposed vertically, and the weather-strip is adapted to be raised and lowered to secure the desired frictional engagement. This adjustment also obviates the necessity of boring a large number of perforations in the door and disfiguring the same.

The weather-strip is normally held elevated when the door is opened by means of a spring 9, disposed horizontally and provided with a vertical shank or stem 10. The spring is bowed, its central portion fitting against the door and its ends engaging the weather-strip at the inner face thereof. The shank or stem 95 is provided with a slot 11, through which passes the fastening device of the adjacent leaf or plate. The spring is flattened or straightened when the weather-strip is swung downward against the door, and there is no liability 100

of subjecting it to too great a strain by this operation. The angle or inclination of the weather-strip may be readily changed by adjusting the spring vertically and varying the distance between the same and the hinged edge of the weather-strip.

When the weather-strip is applied to a hinged door, as illustrated in Figs. 1 to 3, inclusive, it is provided adjacent to the free edge 10 of the door with a curved portion or cam 12, formed by partially severing the material of the weather-strip and bending the severed portion downward or inward when the said weather-strip is constructed of metal; but the 15 cam may be formed in any other desired manner, as will be readily understood. The curved portion or cam is arranged to engage the strip 13 of the door frame or casing 14, whereby the weather-strip will be swung downward 20 against the floor or sill when the door is closed.

Having thus fully described my invention, what I claim as new, and desire to secure by Letters Patent, is—

1. A device of the class described comprising a strip, means for hinging the same to a door, and a spring interposed between the door and the strip to support the latter in an elevated position when the former is open, said spring being adjustable to vary the angle 25 or inclination of the weather-strip, substantially as described.

2. A device of the class described comprising a hinged weather-strip and means for yieldably engaging the strip to support the same at an elevated position when a door is open, said means being adjustable to vary the angle or inclination of the strip, substantially as described.

3. A device of the class described comprising a strip, a leaf or plate hinged to the strip, 40 a spring engaging the strip and provided with a shank or stem arranged adjacent to the leaf or plate, and means for securing the leaf or plate and the spring to a door and for adjusting them either simultaneously or independently, substantially as described.

4. A device of the class described comprising a strip, a leaf or plate hinged to the strip and provided with a slot, a curved spring engaging the strip and provided with a shank or 45 stem having a slot registering with that of the leaf or plate, and a fastening device for securing the leaf or plate and the spring to a door, substantially as described.

In testimony that I claim the foregoing as 55 my own I have hereto affixed my signature in the presence of two witnesses.

WILLIAM HENRY ETTER.
